UNITED STATES PATENT OFFICE.

EDWARD R. EDWARDS, OF JERSEY CITY, NEW JERSEY.

SASH-RETAINER.

1,254,891.

Specification of Letters Patent.

Patented Jan. 29, 1918.

Application filed July 8, 1916. Serial No. 108,196.

To all whom it may concern:

Be it known that I, EDWARD ROBINSON EDWARDS, a citizen of the United States, residing at Jersey City, in the county of Hudson and State of New Jersey, have invented a certain new and useful Improvement in Sash-Retainers, of which the following is a specification.

My present invention relates to building construction and more particularly to retainers for sashes whereby the sashes may be held in an adjusted position with respect to their jambs.

The principal object of my invention is to provide an effective retainer for window constructions avoiding the use of weight boxes, parting strips, pulleys, cords and weights, which make the construction expensive, the parts of the retainer being carried by the sash and jamb, and concealed between the parting bead and the stop bead or upright lateral guides for the sash.

Other objects of my invention are to provide a sash retainer which is durable and embodying a minimum number of parts; a retainer embodying spring action which may be readily adjusted to adapt it to the particular construction, and according to the weight of the sash; and, a track embodying depressions so shaped as to facilitate the adjustment of the sash with respect to its jamb, to effect a closed or open position of the window.

Further objects of my invention will appear in the following detailed description, taken in connection with the accompanying drawing, forming a part of this specification, and in which drawing:

Figure 1 is a central vertical sectional view through a portion of a window sash and its jamb, and showing a sash retainer embodying my invention in operative relation thereto, parts being shown in elevation to more clearly disclose the manner in which the parts coöperate to attain the object in view.

Fig. 2 is a sectional view on the line 2—2 of Fig. 1.

Fig. 3 is a perspective view of a frame forming one of the elements of my invention.

Fig. 4 is a perspective view of a track to be carried by one of the members of the window.

In the drawing, where similar characters refer to similar parts throughout the views,

A designates one member of a window, such as a sash; B another member of the window, such as a jamb; C an upright lateral guide for the sash A, such as a parting bead; D another upright lateral guide, such as a stop; E a track; and F a keeper coöperating with said track to retain the sash in an adjusted position with respect to its jamb.

In the example shown I prefer to mount the track E in a groove 5 formed longitudinally of the upright jamb B, and to carry the keeper F by the sash A, although it is to be understood that this arrangement may be reversed without departing from the spirit of my invention. Accordingly, the sash A is provided with an enlarged horizontal recess 6, and a smaller horizontal recess 7 contiguous thereto, said recesses being open to the face 8 of sash A, confronting the jamb B.

The keeper F may comprise a frame 9, secured to the sash A, as by screws 10, and includes projections 11 which provide spaced, oppositely disposed guide-ways 12; a reciprocable member 13, such as a fork including a stem 14 which extends into the smaller recess 7; an anti-friction device, such as a roller 15, carried by member 13, as through axle 16, the end portions of which extend into the guide-ways 12; an abutment or washer 17 about stem 14 and at the mouth of recess 7; and, an expansion spring 18 about stem 14, engaging the abutment 17 and acting upon the member 13 to yieldably protract the anti-friction device or roller 15 into engagement with the track E, or so that said roller will enter the depressions in jamb B, as hereinafter described. As clearly shown in Fig. 3, the frame 9 may comprise a main body portion 19, having perforations 20 for the screws 10, and an elongated recess 21 through which anti-friction device 15 extends, laterally of the face 8 of sash A, the extensions 11 projecting from the main body portion 19, have shoulders or ledges extending across the inner faces of the extensions 11 which are recessed as at 22 to accommodate the end portions of fork 13. By this construction, the anti-friction device or roller 15 is mounted so as to be protractile and retractile, with respect to the member it is carried by.

Referring now to the track E, it may be made of band metal so shaped as to provide a plurality of depressions 23 on its face con-

fronting the sash A, said depressions abrupt at their lower junctures 24 with the outer face of the track, and sloping gradually at their upper junctures 26, with said face, as 5 clearly shown in Fig. 1 of the drawing. Thus, as the sash A is moved with respect to the jamb, the anti-friction device 15 rides over the face of the track, and enters the depressions 23. By this arrangement of abrupt 10 and sloping junctures, the sash may be easily moved so that the anti-friction device 15 moves out of any depression, yet the keeper retains the sash in an adjusted position owing to the spring 18 protracting the 15 anti-friction device. The sash may be easily lowered with the anti-friction device riding out of the depression, owing to the weight of the sash facilitating the downward movement. It is understood that the spring 18 is 20 of that strength to withstand casual displacement of the window from an adjusted position due to the force of gravity. The track E is provided with a plurality of perforations 27 to receive screws, such as shown 25 at 28, to retain the track in groove 5 of the jamb B, it being understood that the groove 5 is deepest as at 29, to receive the body of track E, where the depressions occur. In some instances, the track E may be dispensed with, its main function being to resist wear due to constant raising and lowering of the sash, and under which conditions the other member of the window, that is the jamb B, in the present example would 30 be provided merely with depression 29.

In assembling, the spring 18 and washer 17 are arranged about stem 14, with the fork 13 arranged in operative relation to frame 9. The frame is then disposed, with the 40 stem 14 extending into recess 7, whereupon the screws 10 are placed and turned tight. It is to be observed that the axis of recess 7 need not be accurately formed with respect to the line of reciprocation of fork 13, the 45 stem 14 being guided by washer 17, which, in combination with the spring 18 aline the axis of stem 14 into parallelism with the faces of guide-ways 12. This is important in the assemblage of a device of this character so that it will operate without binding. Because of this construction, the 50 device may be assembled into operative re-

lation to the window by one not necessarily skilled in the art. Should the spring 18 become weak due to constant use, the sash can 55 be easily removed by detaching the stop D, moving the window so that the anti-friction device 15 engages the face of track E, whereupon the sash may be swung laterally. The frame 9 may then be removed and a washer, 60 not shown in the drawing, placed into abutting relation with washer 17, compressing the spring 18. By replacing the frame 9, together with the elements carried thereby, the retainer is again in readiness for use and 65 adapted to serve efficiently as a retainer.

It is to be understood that the retainer may or may not be duplicated at each upright of the sash and its confronting jambs. 70

Changes in details may be made without departing from the spirit or scope of my invention; but,

I claim:

In a sash retainer, the combination with an element of a window provided with a 75 recess and a bore at the inner end of the recess communicating therewith, of a plate adapted to be secured over the recess and having an opening therethrough and provided at opposite sides of the opening with 80 pairs of spaced-apart projections extending into the recess and forming guide-ways at the opposite sides of the opening, a fork slidably arranged between the pairs of projections, a roller mounted in the fork, a 85 spindle extending transversely through the fork for supporting the roller and projecting beyond the ends thereof into said guide-ways, a spring surrounding said stem, and a washer carried upon the stem 90 against the inner end of the spring and adapted to bear against the inner face of the recess to retain the spring in position and center the stem in line with the plate, said plate having ledges provided with recesses 95 at the opposite sides of the opening therethrough adapted to receive the forward end of the fork therein when projected by said spring to prevent injury to said spindle when the roller is projected through said 100 plate.

EDWARD R. EDWARDS.
